H. H. VICKERS

TOBACCO USER'S APPLIANCE

Filed March 30, 1922

Inventor:
Harry H. Vickers
by *Bob Stickney*
Attorney

UNITED STATES PATENT OFFICE.

HARRY H. VICKERS, OF CORONA, NEW YORK.

TOBACCO-USER'S APPLIANCE.

Application filed March 30, 1922. Serial No. 548,242.

To all whom it may concern:

Be it known that I, HARRY H. VICKERS, a citizen of the United States, residing in Corona, Long Island, in the county of 5 Queens and State of New York, have invented certain new and useful Improvements in Tobacco-Users' Appliances, of which the following is a specification.

This invention relates to means to enable 10 a smoker to make convenient temporary disposition of a partially-consumed cigar.

A lighted cigar is apt to be deposited where it can burn a desk or table or papers lying thereon, and, moreover, is apt to get 15 brushed off from the table and possibly to start a fire smouldering. In many cases, even where there is no other harm resulting, it is likely to continue to smoke, with possible annoyance to visitors. Besides, the 20 cigar slowly consumes, thereby incurring waste. If the burning end of the cigar is knocked off, it is liable to smoulder and possibly burn a hole in a carpet, or even to set fire to a building.

25 It is sometimes the case that after smoking a part of the cigar, the smoker does not wish to continue; but owing to these drawbacks, he is apt to keep on smoking until the cigar is used up, thereby really incurring an unnecessary waste.

Another drawback is that dust settles 30 rapidly upon the cigar, particularly the moistened end thereof, thus making it distasteful for the smoker to use it again. Besides, the moistened end of the cigar is apt 35 to come into contact with a surface which may be the abode of germs, so that, upon again smoking the cigar, the user might contract a disease therefrom.

40 An object of the invention is to provide a simple, efficient, inexpensive and attractive device for overcoming these and other difficulties.

45 Other features and advantages will hereinafter appear.

In the accompanying drawings,

Figure 1 is an elevation, and Figure 2 a 50 partial plan, of the present improvements carried out in one form.

Figure 3 is a diagrammatic perspective view of the preferred form of the invention, the device being shown open canted to an upright position for the sake of disclosing clearly the interior thereof.

Figure 4 is a plan of the preferred form 55 of the present invention, and Figure 5 is a perspective view of the same.

Figure 6 is an end view of the same, showing the device open and a cigar therein.

Figure 7 is a sectional view of the device 60 closed.

One of the main features of the invention is in the nature of a closed repository 10 for the partially-consumed cigar 11. This repository is in the form of a tube having a 65 capacity for one cigar and comprising a segmental floor portion 12 and a segmental or semi-cylindrical cover portion 13. The cover portion is preferably hinged at 14 to the floor portion. The general conformati- 70 on of the repository may be that of a cylindrical tube. The pivoted tubular lid portion and the tubular floor or box portion may be concentric with the pivotal axis 14 of the tube, so that, when the repository is 75 open, the floor portion 12 is seen nested within the lid portion 13, as indicated dia- grammatically at Figure 3. The cover has ends 14^a, and the floor portion or member has ends 14^b, confined between the ends 14^a, 80 to render the end portions of the repository substantially air-tight.

Within the repository may be fixed a cigar-rest in the form of a tray 15 to receive the partially-burned cigar 11, this tray 85 supporting the cigar above the floor of the repository. This prevents the moistened end of the cigar from contacting with the floor, and conduces to the sanitary character of the repository.

90 In use, the lid 13 may be turned back and the cigar, still burning, may be deposited upon the tray 15, and then the lid may be closed; and the snap 16 may catch over a projection 17 on the floor portion, and hold 95 the device closed in substantially air-tight condition. This avoids the necessity of hunting for a place to deposit the burning cigar where it will not scorch or set fire to anything, and where it will keep clean. The 100 cigar will be promptly quenched, for lack of air supply, and the smoke therefrom will be confined within the repository, which is a desideratum. The cigar is protected from dust and kept clean, ready for subsequent 105 use. The invention enables a substantial economy to be effected, since it is the prevailing practice to throw away partially-burned

cigars; and often to keep on smoking merely to use up the cigar.

The front of the repository may be fixed to a support 18, whereby it is attached to an ash-tray 19, thus producing an article for desk or table ornament, and also conducing to the convenience of the device. The support or mount 18 extends from the front of the portion 12 down to the base 19, to permit the cover 13 to swing between the portion 12 and the base 19, Figure 6. The cigar-rest 19^a is for temporary use while the cigar is being smoked, while the cigar-rest 15 and the repository 12, 13 are both for permanent use after the smoking is concluded. The repository may be mounted above and back of the ash-tray, upon which a rearwardly-extending foot or base 20 may be provided. The repository and the permanent rest 15 extend along one border of the ash-tray. The device is also useful as a paper-weight; and when intended for such purpose the ash-tray may be omitted in some cases.

It is to be noted that the permanent cigar-rest 15 has the further advantage that it supports the cigar at such a high elevation that its sides extend well above the top edges of the respository when it is opened, as will be understood by comparing Figures 3 and 6, and hence there is clearance for the fingers above the edges of the open repository, so that the fingers may pick the cigar right off from the device without the necessity of attempting to insert the fingers between the cigar and the inner sides of the portion 12.

In another form of the invention, Figures 1 and 2, the floor portion 21 of the repository may be telescoped within the open end of a tubular box 22 which is closed at the other end at 23, said floor 21 having at one end a flange, cap or device 24 to close the repository when said floor portion 21 is pushed within the tube or cover portion 22. The cigar in this case may rest upon the tray 15 in the bottom of the portion 21; and the tubular cover portion 22 may be fixed or mounted upon a base 25 to serve as a desk ornament and paper-weight. The two parts may be prevented from relative rotation when the telescope is closed, by means of a tooth 26 on the inside member to engage a notch 27 in the end of the outside member; and the inside member may be provided with a finger-piece or handle 28, whereby it may be pulled out.

Variations may be resorted to within the scope of the invention, and portions of the improvements may be used without others.

Having thus described my invention, I claim:

1. A repository for a partly-burned cigar, said repository in the form of a tube con-

structed of parts fitted together in a manner to permit the tube to be opened for depositing and withdrawing the cigar, said repository comprising a floor portion and a cover portion, each in the form of a segment of a tube, said portions hinged together, said floor portion having ends, and said cover also having ends, said portions nesting one within the other when the device is opened, a base forming a mount for said repository, and a support extending from said base to the front of said floor portion, to permit the cover portion to swing into a position between the floor portion and the base. 70 75

2. A desk or table article for smokers' use, comprising a base and a cigar repository extending in cumbent position over said base and supported thereby, and having the form of a tube with closed ends, said tube comprising two longitudinal portions hinged together, one of said portions serving as a receptacle for the cigar, and the other of said portions serving as a lid therefor, and a cigar-rest in said receptacle and raised from the floor thereof. 80 85

3. A desk or table article for smokers' use, comprising a base, a permanent cigar-rest, and a cigar-repository in the form of a tube with closed ends, said base supporting both said permanent cigar-rest and said tube, said tube extending in cumbent position over said base and having said permanent cigar-rest therein, said tube comprising upper and lower longitudinal portions hinged together, the lower of said portions having a floor above which said permanent cigar-rest is raised, so as to support the cigar-rest with its ends out of contact with said floor, and the upper of said portions serving as a lid. 90 95 100

4. A desk or table article for smokers' use, comprising a base, a permanent cigar-rest, and a cigar-repository in the form of a tube with closed ends, said base supporting both said permanent cigar-rest and said tube, said tube extending in cumbent position over said base and having said permanent cigar-rest therein, said tube comprising upper and lower longitudinal portions hinged together, the lower of said portions having a floor above which said permanent cigar-rest is raised, so as to support the cigar-rest with its ends out of contact with said floor, and the upper of said portions serving as a lid, 110 115 said base in the form of an ash-receiver, and said repository and said cigar-rest both extending along one border of said ash-receiver.
